(57) **CLAIM**

The ornamental design for a distributor as shown and described.

DESCRIPTION

FIG. 1 is a front view of the ornamental design for a distributor of indeterminate length;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is an upper, front isometric view thereof;

FIG. 8 is an upper, rear isometric view thereof; and

FIG. 9 is a lower, front isometric view thereof.

FIG. 10 is a front view of the ornamental design for a distributor of indeterminate width;

FIG. 11 is a left side view thereof;

FIG. 12 is a right side view thereof;

FIG. 13 is a rear view thereof;

FIG. 14 is a top view thereof;

FIG. 15 is a bottom view thereof;

FIG. 16 is an upper, front isometric view thereof;

FIG. 17 is an upper, rear isometric view thereof; and

FIG. 18 is a lower, front isometric view thereof.

FIG. 19 is a front view of the ornamental design for a distributor of indeterminate length and indeterminate width;

FIG. 20 is a left side view thereof;

FIG. 21 is a right side view thereof;

FIG. 22 is a rear view thereof;

FIG. 23 is a top view thereof;

FIG. 24 is a bottom view thereof;

FIG. 25 is an upper, front isometric view thereof;

FIG. 26 is an upper, rear isometric view thereof; and

FIG. 27 is a lower, front isometric view thereof.

Each embodiment of the distributor depicted herein is shown having break lines along one or more directions in one or more locations and any portion of the design not shown in the drawings forms no part of the claimed design.

1 Claim, 27 Drawing Sheets

Related U.S. Application Data

continuation-in-part of application No. 29/866,115, filed on Aug. 29, 2022, now Pat. No. Des. 1,046,070.
